UNITED STATES PATENT OFFICE.

FRANK D. CHADWICK, OF OTTAWA, ILLINOIS.

AUTOMATIC SAND-DRYING EQUIPMENT.

Application filed April 4, 1928. Serial No. 267,213.

My invention relates to automatic sand drying equipment and has for its object the production of such equipment in which a large quantity of wet sand or other similar material can be dumped or conveyed into a suitable large receiving means by any of the usual means employed for such purposes, said material being retained on a novel means which not only supports the entire 10 loading of the material thus dumped in but contains a novel and extremely simple and extremely efficient means for removing the moisture from the material and permitting it, as it dries, to flow through into a belt 15 conveyor system which removes it to the dry storage or cars for shipment.

Its further object is to produce such an equipment which is very simple in construction and comprised of units having a large 20 exposed vertical drying surface per unit of horizontal area as well as per unit of cubic contents of material exposed to said heating surface, and these units are so connected and located in relation to each other so that any 25 one unit can be removed without in any manner disturbing any of the remaining units.

It is well known that the moisture in this material is extremely corrosive and so that 30 the material such units are made of is wasted away rapidly so that these units need frequent replacements and before my invention it was necessary at times to remove many of the previously made units before reaching 35 the worn units which generally resulted in a loss of these units making it necessary to replace them by means of new units which it is evident was very expensive all of which is avoided by my novel construction.

40 A further object of my invention is the production of such an equipment wherein while the large area of vertically positioned heating surface is exposed to a small area of horizontal material area, at the same time 45 a large area of ventilating space per unit of material is also provided to remove the moisture as it is driven from the previously wet sand or other material.

50 A further object of my invention is the production of such an equipment that is not only highly efficient but is extremely simple and inexpensive to construct and exceptionally durable and therefore not subject to as frequent replacements of units that was always necessary with such equipment before 55 my invention.

I attain these objects by the means shown in the accompanying drawings in which:

Fig. 1 is a side view of my automatic sand drying equipment, having a part of the front 60 side wall removed to show the arrangement of the units comprising same.

Fig. 2 is a vertical cross sectional view along a line AB of Figure 1.

Similar parts are represented by the same 65 numerals throughout the several views.

In the drawings 1 represents the loading chamber of my automatic sand drying equipment and 2 is the usual large quantity of sand or like material to be treated. The 70 chamber 1 is supported by the I beams 3 which rest on similar beams 4 which carry the loadings to the usual walls of the building or suitable piers which are not shown in the drawings.

75 6 is one of the plurality of special vertical units which are preferably made of cast iron of such shape that they have external apertures 5 and that they have an interior divided heating space for a suitable heating 80 medium such as steam, which are separated from each other by the spaces 7 in each of the individual integral sectional parts 8 comprising the complete unit 6, the units 8 being connected with each other and communicating with each other both at the top and bottom of said individual units so that the steam or heating medium can readily 85 reach the entire interior surface or spaces.

90 Between each of these vertically positioned units 6 is a horizontally positioned unit 9 which is suitably supported by means of supports 10 and holds the sand back in contact with the vertically positioned units 6 until it is sufficiently dried to permit it to 95 pass by between 9 and the units 6. When it does so it encounters a plurality of smaller individual units 11 which may be similarly heated by an internal medium or may act as regenerators by taking the heat from the 100 highly heated sand as it passes through them and in turn giving back the heat to assist in drying some of the sand still having some moisture in it that worked through too rapidly from above after flow had previously been checked by such a condition of moisture.

105 The flow of sand through my sand drying equipment is more or less pulsating in action, that is, the flow while it is continuous varies, is first larger then smaller 110 etc. which regulation of flow is due to this regulating regenerative idea which thus

gives a much higher quality, as far as dryness is concerned, to the material dried by my equipment.

Immediately above each of my vertically positioned units 6, I provide an angular shield 12 which acts as a distributor of the wet material in order to properly distribute the sand between the individual parts 8 of said units 6 as well as to assist in supporting the heavy loading due to the material 2. The shields 12 properly distribute the wet material so as to retain as large a part of the ventilating spaces 5 and 7 as possible so that there is a maximum of ventilating space which is continuous through the units 6. Air entering the opening 13 in the wall 14 of chamber 1 can pass through said ventilating areas until it enters the flue 15 through aperture 16 and passes out through the chimney 17. 18 is a suitable piece of leather or rubber belting which is inserted as shown to keep the sand from escaping through the openings 13 and 15. 19 is a hopper for receiving the dried sand which passes out through apertures 20 in the bottom of the hopper 19 into a conveyor belt 21 to the usual storage or car loading equipment. 22 indicates a large pipe for supplying steam and 23 indicates a valve for shutting off the steam from a unit to replace same when necessary.

From the above description it will be seen that my automatic sand drying equipment will successfully handle large quantities of wet material and will not permit it to pass unless it is thoroughly dried and that the units comprising same are very accessible and durable and that the whole construction is extremely simple and inexpensive to build.

I claim:

1. In automatic sand drying equipment, a chamber, a plurality of beams supporting said chamber, a plurality of heating units each comprising a plurality of integral vertically positioned sectional parts having centrally disposed ventilating apertures placed adjacent to each other and internally and operatively connected with each other, said units extending in length across said chamber and having spaces between said units, horizon-

tally positioned individual heating elements placed between said units and a regenerative delivering means supported on said beams.

2. In automatic sand drying equipment, a chamber, means for supporting said chamber, regenerative delivery means on said supporting means, a plurality of heating units each comprising a plurality of integral vertically positioned sectional parts having centrally disposed ventilating apertures placed adjacent to each other and internally and operatively connected with each other said units extending across said chamber and having spaces between said units, horizontally positioned individual heating elements placed between said units and distributing means associated with heating units.

3. In automatic sand drying equipment, a chamber, supporting means for said chamber, regenerative delivery and regulating means adjacent to said supporting means, a plurality of heating units each comprising a plurality of integral vertically positioned sectional parts having centrally disposed ventilating apertures placed adjacent to each other and internally and operatively connected with each other said units extending across the chamber and having spaces between said units, horizontally positioned individual heating elements placed between said units, distributing means associated with the heating units and means for removing the vapors given off around said heating units.

4. In automatic sand drying equipment, a chamber, supporting means for said chamber, regenerative delivery and regulating means adjacent to said supporting means, a plurality of heating units each comprising a number of integral vertically positioned sectional parts having centrally disposed ventilating apertures placed adjacent to each other and internally and operatively connected with each other and having spaces between said units, horizontally positioned heating elements placed between said units, distributing means associated with said heating units and a stack connected with the said ventilating apertures.

FRANK D. CHADWICK.
